UNITED STATES PATENT OFFICE.

ALBERT ORLAN DOLSON, OF IMPERIAL, CALIFORNIA.

CONCRETE CONSTRUCTION.

Application filed February 19, 1923. Serial No. 620,103.

To all whom it may concern:

Be it known that I, ALBERT ORLAN Dolson, a citizen of the United States, residing at Imperial, in the county of Imperial 5 and State of California, have invented a new and useful Concrete Construction, of which the following is a specification.

This invention relates to improvements in building wall constructions.

An object of this invention is to provide an improved building wall construction in which there are inner and outer spaced walls forming a type of hollow wall, and between which concrete beams and columns may be 10 poured.

Another object of this invention is to provide a slab which can be used in constructing a hollow wall and which will enable concrete beams and columns to be poured 20 in the hollow wall.

With the foregoing and other objects in view which will be made manifest in the following detailed description and specifically pointed out in the appended claims, reference is had to the accompanying drawings 25 for an illustrative embodiment of the invention, wherein:

Figure 1 is a sectional view in plan of a portion of the wall of the improved construction, and may be considered as taken upon the line 1—1 of Fig. 4,

Fig. 2 is a view similar to Fig. 1, the inner and outer walls being shown as spaced apart, illustrating the manner in which the 35 slabs forming the walls are assembled,

Fig. 3 is a horizontal section taken substantially on the line 3—3 of Fig. 4,

Fig. 4 is a vertical section taken on the line 4—4 of Fig. 1, and

Fig. 5 is a perspective view of one of the 40 slabs.

Referring to the accompanying drawings wherein similar reference characters designate similar parts throughout, the improved 45 wall is built up of two types of slabs, indicated generally at A and B. Each of the slabs consists of a slab 10 formed of concrete or similar self-hardening plastic material. A rib 11 is formed on the slab in a vertical position at approximately its center, and extends slightly below its lower edge. The upper end of the vertical rib 11 terminates some distance below the top edge 50 of the slab 10. On the slab there are also preferably formed two horizontal ribs indicated at 12 and 13 respectively. The upper

horizontal rib 12 extends horizontally from the top of the vertical rib 11 toward one of the side edges of the slab 10. The lower horizontal rib 13 extends from the vertical 55 rib 11 some distance above its bottom toward the same side edge of the slab 10. The slabs A and B differ from each other in the following manner. On the slabs A the ribs 12 and 13 extend from the vertical rib 11 60 towards the left hand side edge as shown in Fig. 5, while the slabs B have their horizontal ribs extending from the vertical rib 11 toward the right hand side edge of the slab 10.

In the vertical rib 11 there may be imbedded one or more vertical reinforcing rods 14, which reinforcing rods extend upwardly above the upper end of the rib 11. A similar reinforcing rod or rods 15 may be imbedded 65 in the slab 10 at the back of the rib 11, and these reinforcing rods have their upper ends bent outwardly adjacent the upper ends of the reinforcing rods 14. Suitable tie wires are preferably imbedded in 70 the vertical ribs 11 passing around the vertical reinforcing rods 14. Adjacent the side edges of the slabs 10 there are preferably positioned small rods 16 around which the tie wires 17 may be tied in assembling the 75 slabs to form a wall. Suitable horizontal reinforcing rods, such as are indicated at 80 18, may be imbedded in the forward sides of the horizontal ribs 12 and 13 to reinforce them if so desired.

Referring now particularly to the left hand sides of Figs. 1, 2 and 3 the slabs are assembled with the slabs A forming the outer side of the wall and the slabs B forming the inner side of the wall. The vertical 85 ribs 11 upon the slabs B are so arranged as to be positioned opposite the joints between the slabs A, and by this arrangement it will be noted that the upper horizontal ribs 12 upon the slabs A and B extend completely 90 across the space between the slabs 10 of the slabs A and B and cooperate to form a continuous beam soffit located below the top edges of the slabs. On this continuous beam soffit suitable reinforcing rods 20 may be 95 positioned and concrete 21 may be poured thereon, thus forming a continuous reinforced concrete beam adjacent the upper ends of the slabs, which ties the slabs together, forming a rigid wall construction.

In such constructions the lower horizontal 100 rib 13 serves very little purpose other than

being a spacer, spacing the lower portion of the slabs 10 on the slabs A and B. However, where there is to be a window opening, such horizontal ribs may be used to form a lintel. 5 When it is desired to form a column between the inner and outer walls, the slabs A are positioned upon the inside so that they form the inside surface of the wall. In other words where the column space is to occur, as 10 at C, a slab A is positioned on the inside of the wall so that its side edge contacts with the side edge of the slab B, and in a similar manner a slab B is positioned on the outside of the wall so that its side edge contacts with the side edge of the slab A. The wall may be continued to be built in this manner with the slabs B arranged on the outside and the slabs A arranged on the inside until a next 15 column space is desired, where the slabs are again reversed. This reversal of the positions of the slabs causes a column space to be left between two adjacent vertical ribs 11, which space extends continuously from top to bottom between the slabs. Suitable reinforcing rods 22 may be positioned therein and the concrete 21 used in forming the reinforced concrete beam can be poured into the column space so as to completely fill it. By this construction a column will be cast between the inner and outer surfaces of the wall and will be cast at the same time that the beam is poured, so that it will be an integral construction between the column and the beam. 30

35 From the above it will be appreciated that an improved form of construction may be easily, quickly and cheaply assembled, and that the beams and columns of reinforced concrete can be poured between the inner and outer surfaces of the walls, strengthening it, and serving to tie or bind the inner and outer slabs together. When the slabs are arranged one course above another, the lower projecting ends of the vertical ribs 11 are positioned on top of the concrete beam formed between the slabs of the next lower course, and this projecting end assumes a position between the upper ends of the slabs of the next lower course. The improved construction enables all of the slabs to be formed at a central plant and shipped to the job where they are assembled. It will be readily appreciated that the slabs may be quickly placed in their proper position and that a relatively small amount of concrete is required to be poured at the job in forming the beams and the columns. 50

60 It will be understood that various changes may be made in the detail of construction without departing from the spirit or scope of the invention as defined by the appended claims.

I claim:

65 1. A building wall comprising inner and outer walls formed of concrete slabs, hori-

zontal ribs formed integral with said slabs some distance below their upper edges and extending completely across the opening between the inner and outer walls, said horizontal ribs constituting beam soffits whereby a continuous beam may be poured thereon between the portions of the inner and outer walls thereabove. 70

2. A building wall comprising inner and outer walls formed of concrete slabs, horizontal ribs formed integral with said slabs some distance below their top edges, said ribs extending approximately half-way across the width of the slab and completely across the distance between the inner and outer walls, the ribs being adapted to fit together when the slabs are assembled to form a continuous beam soffit on which a concrete beam may be poured between the portions of the slabs thereabove. 75

80 3. A building wall comprising inner and outer walls formed of concrete slabs, the vertical joints between the slabs of the outer wall being out of alignment or in staggered relation with respect to the vertical joints between the slabs of the inner wall, horizontal ribs extending across the space between the walls and from the middle of their respective slabs toward a side edge, the ribs being adapted to fit together to form a continuous beam soffit located some distance below the top edges of the slabs, whereby a continuous concrete beam may be poured thereon between the upper portions of the slabs. 90

95 4. A concrete slab for building wall construction comprising a flat slab on which a horizontal rib is formed which is located some distance below its upper edge and extends approximately from its middle toward one side edge, said slab being so constructed that a plurality of such slabs may be assembled forming inner and outer walls between which there is arranged a continuous beam soffit formed by the horizontal ribs. 100

105 5. A concrete slab for building wall construction comprising a flat slab on which a horizontal rib is formed which is located some distance below its upper edge and extends approximately from its middle toward one side edge, and on which a vertical rib is formed which extends from the inner end of the horizontal rib downwardly. 110

115 6. A concrete slab for building wall construction comprising a flat slab on which two horizontal ribs are formed, one being located a short distance below the top edge of the slab, and the other being located a short distance above the bottom edge of the slab, 120 both of said ribs extending from approximately the middle of the slab toward one side edge thereof.

125 7. A concrete slab for building wall construction comprising a flat slab on which two horizontal ribs are formed, one being located 130

a short distance below the top edge of the slab, and the other being located a short distance above the bottom edge of the slab, both of said ribs extending from approximately the middle of the slab toward one side edge thereof, and a vertical rib formed on the slab at approximately its middle extending from the end of the upper horizontal rib down to the end of the lower horizontal rib and to the bottom of the slab.

8. A building wall construction comprising inner and outer walls formed of concrete slabs, the vertical joints of the outer wall being approximately opposite the middle of the slabs of the inner wall, there being horizontal ribs formed upon the slabs which are located some distance below the top

edges and which extend completely across the distance between the walls, and vertical ribs formed upon the middle of each slab 20 adapted to be positioned against the vertical joints between the slabs of the opposite wall, said vertical ribs extending downwardly from said horizontal ribs, the slabs being so assembled that the horizontal ribs fit together to provide continuous beam soffits on which a continuous concrete beam may be poured between the upper portions of the slabs with the horizontal ribs missing at desired intervals, permitting a concrete column 30 to be poured beneath the beam between a pair of vertical ribs on said slabs.

ALBERT ORLAN DOLSON.
